UNITED STATES PATENT OFFICE

RAYMOND BARBAS, OF PARIS, FRANCE, ASSIGNOR TO LA SOCIÉTÉ ANONYME JEAN PATOU, OF PARIS, FRANCE, A CORPORATION OF FRANCE

DESIGN FOR A BOTTLE

Application filed October 11, 1930. Serial No. 37,231. Term of patent 7 years.

To all whom it may concern:

Be it known that I, RAYMOND BARBAS, a citizen of the Republic of France, residing in the city of Paris, France, have invented a new, original, and ornamental Design for Bottle, of which the following is a specification, reference being had to the accompanying drawing, forming a part thereof.

In the drawing:

Fig. 1 is a perspective view of my new design.

Fig. 2 is a side view thereof, Fig. 1 showing the bottle as viewed from either side.

I claim:

The ornamental design for a bottle substantially as shown and described.

R. BARBAS.
